DESIGN FOR A MINIATURE BATTLEFIELD

Dayle R. Butterfield, Chicago, Ill.

Application May 20, 1935, Serial No. 56,915

Term of patent 14 years

To all whom it may concern:

Be it known that I, Dayle R. Butterfield, a citizen of the United States and resident of Chicago, in the county of Cook and State of Illinois, have invented a new, original, and ornamental Design for a Miniature Battlefield, of which the following is a specification, reference being had to the accompanying drawing, forming a part thereof.

Fig. 2 is a longitudinal sectional view through the same substantially on line 2—2 of Fig. 1.

I claim:

The ornamental design for a miniature battlefield, substantially as shown.

Signed at Chicago, in the county of Cook, and State of Illinois, this 17th day of May, A. D. 1935.

DAYLE R. BUTTERFIELD.
